UNITED STATES PATENT OFFICE.

WILLIAM H. HART, JR., OF PHILADELPHIA, PENNSYLVANIA.

MAILING-ENVELOP.

1,179,719.

Specification of Letters Patent. Patented Apr. 18, 1916.

Application filed April 14, 1915. Serial No. 21,355.

To all whom it may concern:

Be it known that I, WILLIAM H. HART, Jr., a citizen of the United States, residing in the city and county of Philadelphia, State of Pennsylvania, have invented a new and useful Mailing-Envelop, of which the following is a specification.

My invention consists of a mailing envelop or package composed of a body and a closing flap therefor, and an additional flap which is adapted to be connected with said closing flap and secured to said body, whereby while the envelop may be held reliably in closed position, it may be opened to inspect the contents thereof without fracturing or injuring the envelop.

The invention is satisfactorily illustrated in the accompanying drawing, but the important instrumentalities thereof may be varied, as long as they are included in the scope of the claim.

Figure 1 represents a rear elevation of an envelop embodying my invention, the same being in closed condition. Fig. 2 represents a rear elevation of a portion of the same in open condition. Fig. 3 represents a longitudinal section on the line $z-z$ Fig. 1. Fig. 4 represents a rear elevation of a portion of the envelop in closed condition. Figs. 5 and 6 represent elevations of detached members.

Similar numerals of reference indicate corresponding parts in the figures.

Referring to the drawings, 1 designates an envelop composed of the body 2 and closing flap 3 therefor, the latter having a transversely-extending slit or opening 4 therein. 5 designates a T-shaped tongue whose head is wider than said slit 4 and whose main length 6 is adapted to be passed through said slit 4 so that when said head is on the inner face of said flap the shoulders 7 of the tongue abut against the walls of said slit 4 and overlap the terminals thereof, whereby the tongue is connected with the flap 3 without gumming and its length 6 extends thereto in downward direction in the position shown in the drawings.

8 designates a supplemental flap which is connected with the flap 3 and has on its inner face on the lower portion thereof adhesive material as at 9, whereby it may be secured to the back 10 of the body of the envelop as a fixture thereof while said supplemental flap is secured to the flap proper 55 by the tongue 5 without any gumming there whatsoever, allowing said flap proper to be

disconnected from the supplemental flap to open the envelop, although the lower portion of said supplemental flap remains connected with the back of the body by the adhesive material employed, as has been stated.

The connection of the flap is as follows:— In the supplemental flap are transversely-extending parallel openings 11, 12 and 13. This leaves between the openings 13 and 12, 65 the cross bar 14, and between the openings 12 and 11, the cross bar 15. Now the main length 6 of the tongue is reeved through the openings 11, 13 and 12, and turned up on the upper wall of the opening 13 and over 70 the cross bar 14 and then tucked into the opening 12 whereby its end is beneath the cross bar 15 against the portion of the tongue rearward of the opening 12, thus securely connecting the supplemental flap with the 75 flap proper of the envelop and retaining the tongue in its locked position, preventing improper separation and disconnection of the flaps.

When the envelop receives merchandise or goods the supplemental flap is caused to adhere to the back of the body by the material 9, thus closing the envelop and retaining its contents reliably therein. Should a post office official desire to inspect said contents 80 he manipulates the tongue whereby it may be drawn through the supplemental flap when the flap proper may be opened exposing said contents, but the supplemental flap remains adhering to the body of the envelop so that the flap proper may be returned 85 to its closing position and the tongue restored to the supplemental flap and interlocked therewith, it being noticed that the envelop and flap are in no wise fractured 90 or injured and so the envelop is available for service to its destination and consequently 95 for re-use if so desired.

While I denominate the device as a mailing envelop it may be used for general business purposes as a package or folder to contain merchandise or goods, and carry or transmit the same in closed condition to its place of destination.

Having thus described my invention what 105 I claim as new and desire to secure by Letters Patent, is:—

In a mailing envelop, a body and a closing flap proper, a supplemental flap, and a tongue having a T-head, said flap proper 110 having therein an opening, with the wall of which said tongue is interlocked by the head

thereof, said supplemental flap having therein a series of parallel openings forming a plurality of cross bars, one below the other, the lower end of said supplemental flap being adapted to be secured to said body, and the upper end remaining free of said flap proper, excepting by means of said head of the tongue, said tongue extending from the flap proper and being adapted to be

passed behind the plurality of cross bars 13 turned up from the lower cross bar in front thereof, and tucked behind the upper cross bar. 8
